[57] CLAIM

The ornamental design for a video camera cradle mount, as shown and described.

DESCRIPTION

FIG. 1 is a front, right side, and top perspective view of a video camera cradle mount showing my new design, the portion of the figure shown in broken lines representing a video camera and tripod and forming no part of the claimed design;

FIG. 2 is a rear elevational view thereof;

FIG. 3 is a front elevational view thereof;

FIG. 4 is a right side elevational view thereof;

FIG. 5 is a left side elevational view thereof;

FIG. 6 is a bottom plan view thereof; and,

FIG. 7 is a top plan view thereof.

FIG. 2

FIG. 3

FIG. 4**FIG. 5**

FIG. 6**FIG. 7**
